UNITED STATES PATENT OFFICE.

WILLIAM C. CARR, OF BUFFALO, NEW YORK.

ELEVATOR TRUCK.

1,407,124.

Specification of Letters Patent. Patented Feb. 21, 1922.

Application filed August 24, 1920. Serial No. 405,695.

To all whom it may concern:

Be it known that I, WILLIAM C. CARR, a citizen of the United States, residing at Buffalo, in the county of Erie and State of New York, have invented new and useful Improvements in Elevator Trucks, of which the following is a specification.

This invention relates to trucks and more particularly to that type of trucks which are used for transportation purposes, as well as raising and lowering their load platforms from one position to another to facilitate loading and unloading thereof.

The principal object of this invention is the provision of an improved electrically-controlled elevating platform for such trucks for lifting or tiering the load from a lower to a higher level or vice versa.

Other objects are to provide an elevating platform of this character which is simple, strong and durable in construction, which is efficient in operation, and which is conveniently controlled from the operator's platform.

A further object of the invention is to provide a brake in conjunction with the elevating mechanism for stopping the platform instantly in any desired position.

A still further object is the provision of automatic means for stopping the elevating platform when it reaches the end of its predetermined travel.

Other objects are to provide certain novel details of construction which will be fully hereinafter described and claimed.

In the accompanying drawings:

Figure 1 is a side elevation of a truck embodying my improvements. Figure 2 is a top plan view thereof. Figure 3 is a front view thereof. Figure 4 is a fragmentary transverse vertical section, on an enlarged scale, taken on line 4—4, Fig. 1. Figure 5 is an enlarged fragmentary longitudinal section on line 5—5, Fig. 2. Figure 6 is a fragmentary transverse section of the elevating platform on line 6—6, Fig. 5. Figure 7 is an enlarged fragmentary horizontal section on line 7—7, Fig. 1. Figure 8 is an enlarged fragmentary vertical section on line 8—8, Fig. 2. Figure 9 is a transverse section on line 9—9, Fig. 8.

Similar characters of reference indicate

corresponding parts throughout the several views.

I have shown my invention applied to a 55 motor propelled truck, although it is applicable to other types of trucks as well. The numeral 15 represents the main frame or body of the truck which may be of any suitable construction, and which is provided at 60 its rear end with drive wheels 16 and at its front end with steering wheels 17. The latter are suitably mounted on an axle 18 supported at the extreme forward end of the side channels 19, 19 of the truck frame. The 65 wheels 16 are preferably driven from an electric motor 20 through the medium of a worm and worm wheel, not shown. A battery 21 supplies current to the motor which is controlled by a suitable controller 22. 23 70 indicates the operator's platform from which position the truck, as well as the elevating platform, is controlled.

The elevator frame consists of a pair of upright supporting columns 24, 24, which 75 are preferably constructed of channel iron, and which are rigidly secured at their lower ends to the side-channels 19 of the truck frame, while their upper ends are reliably held by diagonal braces 25 and intermediate 80 horizontal braces 26.

27 represents generally the elevating platform which extends forwardly from the supporting columns and which is raised and lowered by means which are preferably constructed as follows:

28 indicates a vertically disposed screw arranged centrally between the supporting columns 24 and journaled at its lower end in a step bearing 29 formed in the base of a 90 housing or gear case 30, while its upper end is journaled in a self-aligning bearing 31 arranged in the transverse supporting head 32 of said columns. This screw is threaded substantially its entire length, its lower end 95 above the step bearing being provided with a squared portion 33 upon which is mounted a worm wheel 34 for turning the screw. This worm wheel is arranged within the housing 30 and meshes with a worm 35 journaled in bearings in said housing. Any suitable means may be employed for rotating the worm to drive the screw in either direction, but as shown in the drawings, an electric

2
motor 36 of the reversible type is preferably provided which transmits motion to said worm by a sprocket chain 37 passing around sprocket wheels 38 and 39 mounted on the 5 motor and worm shafts, respectively.

As shown in Figs. 4 and 5, the housing 30, in which the lower end of the screw 28 is supported, is pivoted about its horizontal transverse axis to provide for misalignment 10 of the screw when the frame is stressed. For this purpose, the opposite sides of the housing are provided with trunnions 40 which are journaled in the adjacent portions of the supporting columns and side channels 19 of 15 the truck frame. Extending rearwardly from the housing is an arm 41 provided at its free end with an opening 42. Secured in the cross piece 43 of the truck frame is a depending screw or bolt 44 which passes 20 through the opening of said arm and is provided below the latter with stop nuts 45. A coil spring 46 surrounding the bolt and bearing at its lower end against the arm 41 and at its upper end against a nut 47 serves to 25 yieldingly permit the housing 30 to oscillate upwardly and provide for misalignment of the screw should the frame be stressed. The nuts 45 act as fixed stops and prevent the housing from oscillating below its horizontal 30 plane.

48, 48 represent a pair of cantilever arms or supporting members which are guided on the supporting columns and which serve to support the elevating platform 27. The 35 preferred means for guiding these arms consists of two sets of rollers 49, 50 which are mounted on the outer ends of upper and lower transverse shafts 51 and 52, respectively, carried by said arms. The upper 40 rollers 49 engage the rear flanges of the supporting columns 24, while the lower rollers 50 engage the opposite or front flanges of said columns, thereby firmly and reliably supporting the arms on said columns. To 45 prevent these arms from swaying laterally, the rollers are provided on their outer sides with flanges 53 which engage the corresponding outer marginal face of the supporting columns.

50 Mounted for universal movement between the upright rear portions of the cantilever arms 48 is a nut 54 which engages the screw 28 for raising and lowering said arms to effect a corresponding movement of the platform 55 27. This nut is provided on opposite sides thereof with trunnions 55, which are journaled in a yoke 56 supported by trunnions 57 on the cantilever arms, the trunnions of said yoke being arranged at right 60 angles to the trunnions of said nut. By thus universally supporting the latter, it can readily accommodate itself to any tilting action or disalignment of the screw due to 65 stresses imposed on the truck body and elevator frame.

By pivotally mounting the lower end of the screw and providing its upper end with a self-aligning bearing, as shown, together with the universally jointed nut co-operating with said screw, binding or breakage of the 70 parts is prevented, and uniform running is assured under all conditions.

The nut 54 is provided on one side thereof with an oil reservoir or receptacle 58 which is preferably cast integral with said 75 nut, as shown in Fig. 4, and is of the proper depth to contain a sufficient supply of oil for thoroughly lubricating the screw 28. This reservoir is separated from the threaded bore of the nut by a partition 59, the latter being provided with oil conducting passages 60 which conduct the lubricant from the magazine to the screw. Stuffing glands 61 are arranged at the upper and lower ends of the nut for retaining the lubricant there- 80 in. The oil reservoir is open at its upper end to permit filling thereof, a suitable cover plate 62 normally closing said opening.

The elevating load platform 27, as previously noted, is supported by the cantilever 90 arms and may be of any suitable construction. As shown in Figs. 5, 6 and 7, it is constructed of a U-shaped iron frame 63 which is open at its rear end to permit the same to overhang the side channels 19 of the frame. 95 A platform plate or support 64 is riveted or otherwise secured to the top of this frame and is reinforced lengthwise thereof by longitudinal channels 65. In order to permit the platform to tilt upwardly relatively to 100 the cantilever arms should it strike an obstruction in its path during the lowering movement thereof, the same is preferably pivoted to said arms. For this purpose, pivot plates 66 are mounted on the lower 105 guide roller shaft 52 and between the cantilever arms, the front ends of said plates being secured by bolts 67 to the channels 65 of the platform frame.

As shown in Figs. 1 and 2, the front portion of the platform preferably overhangs the steering wheels 17 to permit of moving the truck into closer proximity to the part to be loaded or unloaded, thereby materially facilitating these operations in an expeditious manner.

The extreme front end of each cantilever arm may be provided with a vertically arranged adjusting bolt 68 which engages the underside of the platform plate 64 and permits of uniformly adjusting the platform to different inclined positions to suit certain working conditions.

The means for controlling the elevating motor 36 for raising and lowering the platform 27 together with the means for stopping the latter in any desired position, are preferably constructed as follows:

Arranged within a box 69 secured to the rear portion of the truck frame 15 is a re- 130

versing switch 70 of any well known type which is in circuit with the battery 21 and the elevating motor to control the rotation of the screw 28 for raising and lowering the 5 elevating platform. The control lever 71 of this switch is connected by a link 72 with one arm of a bell crank lever 73 fulcrumed on the adjacent horizontal brace 26. The other arm of this lever is pivotally connected 10 by a link 74 with the lower end of an upright rod or plunger 75 guided at its lower end in a bracket 76 suitably fastened to said horizontal brace. This rod, which extends substantially to the top of the supporting 15 column 24, is supported at its upper end in a guide bracket 77 suitably secured to the adjacent diagonal brace 25. Connected to the pivot at the lower end of this rod is a depending link 78 which is pivoted at its 20 lower end to a vertically swinging lever 79 fulcrumed on the adjacent portion of the elevating motor. Mounted on the shaft 36^a of the latter is a brake drum 80 adapted to be engaged by a brake-band 81 constructed 25 of two sections hinged at 82 to the motor frame. The free ends of these sections are provided with ears 85 between which is disposed a rotatable cam-block 84 controlled by the lever 79 and adapted to expand the 30 band for releasing the brake drum. A coil spring 85 serves to normally contract the brake band around the drum in the usual manner. The switch 70 and brake band 81 are controlled simultaneously by a conveniently located operating handle 86 fulcrumed at 87 and connected by a link 88 with that arm of the bell crank lever to which the link of the switch control lever 71 is connected. By this arrangement of the 40 parts, it is possible to instantly stop the elevating platform in any desired position, inasmuch as the motor switch and brake are actuated simultaneously by a single movement of the operating handle.

45 The operating handle 86 is normally held in its neutral position, as shown by full lines in Fig. 8, by a centering or return spring 89 which is arranged to be compressed when said handle is moved out of neutral position 50 in either direction of the arrows shown in said figure, and which therefore tends constantly to return the handle to that position when it is unlocked. This spring surrounds the rod 75 and is interposed between opposing followers 90 and 91 loosely mounted on this rod and guided in corresponding openings 92 and 93 arranged in upper and lower guide heads or lugs 94, 95, respectively, formed on the bracket 76. These followers 55 are adapted to normally seat against the opposing faces of the corresponding guide heads. Mounted on the rod above the upper follower 90 and held against movement relatively thereto is a sleeve or abutment 96 60 adapted to abut against said follower to compress the spring 89 downwardly when the operating handle is moved forwardly from its neutral position to cause the elevator to be raised; and mounted on the rod below the lower follower 91 is a sleeve or abutment 97 adapted to abut against said follower to compress said spring upwardly when the operating handle is moved rearwardly from its neutral position to cause the elevator to be lowered.

65 In order to lock the operating handle in its forward or rearward position to hold the motor switch closed and its brake released, during the raising or lowering operation of the elevating platform 27, a suitable locking mechanism, co-operating with the rod 75, is provided which is preferably constructed as follows:

70 95 100 105 110 115 120 125 130

98 represents a locking bolt arranged parallel with the upright rod 75 and guided in the bracket 76, said bolt being coupled with said rod by a tie bar 99 so as to move vertically therewith. This bolt is provided with upper and lower locking notches or grooves 100 and 101 with which a spring catch or locking pin 102 is adapted to interlock. This catch is preferably arranged in a guide 103 projecting rearwardly from the bracket 76. Thus, when the operating handle is moved forwardly to raise the elevating platform, the brake control rod is lowered, moving the locking bolt with it and allowing the spring catch to interlock with the upper notch 100 of said bolt to reliably hold the same in position during the raising of said platform.

To automatically stop the elevating platform when it reaches its highest position without requiring the attention of the operator, the upper end of the rod 75 is provided with an adjustable tappet arm 104 arranged in the path of one of the rear guide rollers 49 of the arms 48, or other adjacent part thereof. Upon striking this tappet arm, the roller forces it from the dotted line position shown in Fig. 8 to the full line position thereof, thereby forcing the rod 75 together with its locking bolt upwardly with it to apply the brake and open the motor switch, and instantly stopping the elevating platform. Simultaneously with this movement, the operating handle is thrown back to neutral position, the spring 89 regulating the return of the same and associated parts to such position. Likewise, provision is made for stopping the platform when it reaches its lowest position. As shown in Fig. 8, the brake actuating lever 79 is provided with an extension 105 arranged in the path of one of the guide rollers 49 or other adjacent part of the platform, so as to be engaged thereby at a predetermined point and cause the brake to be applied and the motor switch to be opened and thereby instantly stop the platform. If desired, this

extension may be provided with an adjusting bolt 106 to be engaged by the roller to permit of stopping the platform in various positions.

- 5 In the operation of this apparatus, assuming the parts to be in their normal position shown by full lines in the drawings, and it is desired to elevate the load platform to the dotted line position shown in Fig. 1, 10 the operating handle 86 is moved forward to the position shown by dotted lines in Fig. 8. This movement, as previously described, releases the elevating motor brake and closes the motor switch, thereby rotating the screw 15 28 in the proper direction to elevate the platform, the spring 89 being compressed and the spring catch engaging the upper notch in the locking bolt 98. Should it be desired to stop the platform before reaching 20 its highest position, the operator simply returns the operating handle to neutral position, which movement applies the brake and opens the motor switch, bringing the platform to an instant stop. However, should 25 it be desired to allow the platform to be elevated to its highest position, it is not necessary that the operator move the handle to restore the parts to neutral position, this being done automatically, as previously described. The lowering of the platform is 30 effected by moving the handle rearwardly, and when it reaches its lowest position it is automatically stopped.

This improved elevating platform truck 35 is easy to operate and very efficient in operation, affording a great saving of time in handling and moving materials from a lower to a higher level and vice versa.

I claim as my invention:

- 40 1. In a truck of the character described, the combination with a truck body and a motor mounted thereon, of an elevator frame carried by said truck body, a screw arranged within said frame, a bearing for the lower 45 end of said screw, pivotally mounted on said frame, a self-aligning bearing for the upper end of said screw, an elevating platform guided on said frame and operatively connected to said screw, and means driven by 50 said motor for rotating said screw.

2. In a truck of the character described, the combination with a truck body and a motor mounted thereon, of an elevator frame carried by said truck body, an elevating platform movable vertically on said frame, a screw journaled on the latter, a nut connected by a universal joint with said platform and engaging said screw, and means driven by said motor for rotating said 60 screw.

3. In a truck of the character described, the combination with a truck body and a motor mounted thereon, of an elevator frame carried by said truck body, an elevating platform movable vertically on said frame, a

screw arranged within said frame, a pivoted bearing member for the lower end of said screw, a nut connected by a universal joint with said platform and engaging said screw, and means driven by said motor for rotating 70 said screw.

4. In a truck of the character described, the combination with a truck body and a motor mounted thereon, of an elevator frame carried by said truck body, an elevating platform movable vertically on said frame, a vertical screw arranged within said frame, a bearing for the lower end of said screw pivotally mounted on said frame, a self-aligning bearing for the upper end of 75 said screw, a nut connected by a universal joint with said platform and engaging said screw, and means driven by said motor for rotating said screw.

5. In a truck of the character described, the combination with a truck body and a motor mounted thereon, of an elevator frame carried by said truck body, a vertical screw arranged in said frame, a bearing for the lower end of said screw pivotally mounted 90 on said frame, a self-aligning bearing for the upper end of said screw, a yieldable connection between said pivoted bearing and said truck body to provide for oscillatory movement of said bearing relatively to said 95 body, a vertically movable platform operatively connected to said screw, and means driven by said motor for rotating said screw.

6. In a truck of the character described, the combination with a truck body and a 100 motor mounted thereon, of an elevator frame carried by said truck body, a supporting member guided on said frame, an elevating platform hinged to said member to swing upwardly thereon and means driven by said 105 motor for vertically moving said member.

7. In a truck of the character described, the combination with a truck body and a motor mounted thereon, of an elevator frame carried by said truck body, a supporting 110 member guided on said frame, an elevating platform hinged to said member to swing upwardly thereon, adjusting means mounted on said supporting member and engaging said platform for regulating the inclination 115 thereof, and means driven by said motor for vertically moving said member.

8. In a truck of the character described, the combination with a truck body and a motor mounted thereon, of an elevator frame 120 carried by said truck body, a vertically movable platform guided on said frame, means driven by said motor for moving said platform, an electric switch included in the circuit of said motor, a brake for said motor, 125 an operating member for manually controlling said switch and brake, and means operatively connected to said switch, brake and operating member for holding said operating member in its neutral position. 130

9. In a truck of the character described, the combination with a truck body and a motor mounted thereon, of an elevator frame carried by said truck body, a vertically movable platform guided on said frame, means driven by said motor for moving said platform, an electric switch included in the circuit of said motor, a brake for said motor, an operating member for manually controlling said switch and brake, a vertically yieldable member operatively connected to said switch, brake and operating member and resisting movement of the latter out of its neutral position, a locking bolt movable with said yieldable member, a spring catch arranged to interlock with said bolt for retaining said operating member in different operative positions, said platform controlling the movement of said yieldable member to simultaneously open said switch, apply said brake and shift said operating member to neutral position. 70
10. In a truck of the character described, the combination with a truck body and a motor mounted thereon, of an elevator frame carried by said truck body, a vertically movable platform guided on said frame, means driven by said motor for moving said platform, an electric switch included in the circuit of said motor, a brake for said motor, an operating member for manually controlling said switch and brake, means operatively connected to said switch, brake and operating member for holding said operating member in its neutral position, and means for retaining said operating member 75 in different operative positions, said platform controlling the movement of said holding means and said retaining means to simultaneously open said motor switch, apply said brake, and shift said operating member to neutral position. 80
11. In a truck of the character described, the combination with a truck body and a motor mounted thereon, of an elevator frame carried by said truck body, a vertically movable platform guided on said frame, means driven by said motor for moving said platform, an electric switch included in the circuit of said motor, a brake for said motor, an operating member for manually controlling said switch and brake, a yieldable member operatively connected to said switch, brake and operating member, and resisting movement of the latter out of its neutral position, and means for retaining said operating member in different operative positions, said platform controlling the movement of said yieldable member and said retaining means to simultaneously open said motor switch, apply said brake and shift said operating member to neutral position. 85
12. In a truck of the character described, the combination with a truck body and a motor mounted thereon, of an elevator frame carried by said truck body, a vertically movable platform guided on said frame, means driven by said motor for moving said platform, an electric switch in the circuit of said motor, a brake therefor, an operating member for manually controlling said switch and brake, a vertically movable member extending substantially the length of said elevator frame and operatively connected to said switch, brake and operating member, means 90 for locking the latter in different operative positions, a spring for resisting movement of said operating member out of its neutral position, and means arranged at the upper and lower ends of said vertically movable member and actuated by said elevator platform to cause said member to be moved in the proper direction to shift said operating member to neutral position. 95
13. In a truck of the character described, the combination with a truck body and a motor mounted thereon, of an elevator frame carried by said truck body, a vertically movable platform guided on said frame, means driven by said motor for moving said platform, an electric switch in the circuit of said motor, a brake therefor, an operating member for manually controlling said switch and brake, a vertically yieldable member operatively connected to said switch, brake and operating member and resisting movement of the latter out of its neutral position, a locking bolt movable with said yieldable member, a spring catch arranged to interlock with said bolt for retaining said operating member in different operative positions, said platform controlling the movement of said yieldable member to simultaneously open said switch, apply said brake and shift said operating member to neutral position. 100
14. In a truck of the character described, the combination with a truck body and a motor mounted thereon, of an elevator frame carried by said truck body, a vertically movable elevator guided on said frame, means driven by said motor for moving said platform, an electric switch in the circuit of said motor, a brake for said motor, an operating member for manually controlling said switch and brake, and movable to different operative positions, and automatic means controlled by said platform for opening said switch, applying said brake and shifting said operating member to neutral position comprising an upright rod, means for supporting said rod and having upper and lower 105 guide heads, followers guided on said rod and normally abutting against said heads, a spring interposed between said followers, abutments mounted on said rod and engaging the outer ends of said followers, tappets 110 mounted on either end of said upright rod and in the path of movement of said platform, and connections from said rod to said switch, brake and operating member. 115
15. In a truck of the character described, 120
- 35 a truck of the character described, the combination with a truck body and a motor mounted thereon, of an elevator frame carried by said truck body, a vertically movable platform guided on said frame, means

- the combination with a truck body and a motor mounted thereon, of an elevator frame carried by said truck body, a movable elevator guided on said frame, means driven by 5 said motor for moving said platform, an electric switch in the circuit of the motor, a brake for said motor, a bell crank lever having one arm connected to said switch and the other arm connected to said brake, and an 10 operating handle connected to said lever for simultaneously actuating said switch and brake.
16. In a truck of the character described, the combination with a truck body and a 15 motor mounted thereon, of an elevator frame carried by said truck body, a movable elevator guided on said frame, means driven by said motor for moving said platform, an electric switch in the circuit of said motor, a 20 brake for said motor, a bell crank lever having one arm connected to said switch and the other arm connected to said brake, an operating handle connected to said lever for simultaneously actuating said switch and brake, 25 and a yieldable member operatively connected to said bell crank lever and resisting movement of the operating handle out of its neutral position.
17. In a truck of the character described, 30 the combination with a truck body and a motor mounted thereon, of an elevator frame carried by said truck body, a movable elevator guided on said frame, means driven by said motor for moving said platform, an 35 electric switch in the circuit of said motor, a brake for said motor, a bell crank lever having one arm connected to said switch and the other arm connected to said brake, an operating handle connected to said lever for simultaneously actuating said switch and brake, 40
18. In a truck of the character described, the combination with a truck body and a motor mounted thereon, of an elevator frame carried by said truck body, a movable elevator guided on said frame, means driven by 45 said motor for moving said platform, an electric switch in the circuit of said motor, a brake for said motor, a bell crank lever having one arm connected to said switch and the other arm connected to said brake, an 50 operating handle connected to said lever for simultaneously actuating said switch and brake, a vertically movable member operatively connected to said bell crank lever, tappets arranged at the upper and lower ends of 55 said member and in the path of said elevator, and yieldable means for resisting movement of said movable member in either direction.
19. In a vertically movable elevating platform, a screw, means for rotating said screw, a nut mounted on said platform and engaging said screw, and an oil reservoir formed in the body of the nut and communicating with the screw. 60
20. In a vertically movable elevating platform, a screw, means for rotating said screw, a nut mounted on said platform and engaging said screw, an oil reservoir formed in the body of the nut, and a partition separating 65 said reservoir from the threaded bore of the nut and provided with oil conducting passages. 70

WILLIAM C. CARR.
